(57) **CLAIM**

The ornamental design for a stand for display screen, as shown and described.

DESCRIPTION

1. Stand for display screen

1.1 : Perspective view in a first state

1.2 : Rear perspective view

1.3 : Front elevation view

1.4 : Rear elevation view

1.5 : Left view, right side view is omitted because it is symmetrical to the left side view

1.6 : Top plan view

1.7 : Bottom plan view

1.8 : Rear perspective view in a state with the stand moved

1.9 : Front perspective view in a state of use with broken line detachable light environment

1.10 : Rear perspective view in a state of use with broken line display screen environment

1.11 : Rear perspective view in a state of use in an alternate configuration with broken line display screen environment

1.12 : Rear perspective view in another alternate configuration with broken line display screen environment
The broken lines indicate portions of the article that form no part of the claimed design.

1 Claim, 12 Drawing Sheets
